UNITED STATES PATENT OFFICE.

WILLIAM J. DOLAN, OF LOVILIA, IOWA, ASSIGNOR OF ONE-HALF TO LEO. W. MALLOY,
OF ALBIA, IOWA.

FENCEPOST.

Application filed April 30, 1920. Serial No. 377,876.

To all whom it may concern:

Be it known that I, W. J. DOLAN, a citizen of the United States, residing at Lovilia, in the county of Monroe and State of Iowa, have invented new and useful Improvements 5 in Fenceposts, of which the following is a specification.

This invention relates to a fence post and more particularly to a metallic fence post 10 and has for its primary object the construction of a post that will be more effectively secured in the earth and more efficiently secure a wire fence in place.

An object of the invention is to provide a 15 post of a simple construction that may be more quickly connected to or disconnected from a wire fence.

A feature of my invention is the use of a 20 retaining plate and anchoring plate for effectively holding the post against movement within the earth and pressure brought to bear against either the post or the wire fence.

With these and other objects in view the 25 invention will be better understood from the following detailed description taken in connection with the accompanying drawing wherein:

Fig. 1 is a front elevation of one form of 30 my invention.

Fig. 2 is a side elevation thereof.

Fig. 3 is a cross sectional view.

Fig. 4 is a perspective view of the retaining plate.

Fig. 5 is a side elevation of another form 35 of my invention.

Fig. 6 is a cross sectional view of the second form of my invention.

Fig. 7 is a sectional view of Fig. 5.

Again referring to the drawing and more particularly to Figs. 1 to 4 inclusive the numeral 1 designates a body of the fence post constructed from sheet steel shaped to provide a plurality of flanges, in this particular instance 3 in number, designated by the numerals 2, 3 and 4. The flange 2 is of loop formation so as to slidably receive the rod 5 and is provided at spaced points with slots 6 for the purpose hereinafter described. Each 45 of the flanges 3 and 4 have their edges formed into open beads 7 so that the body of

the post will be effectively re-inforced and besides that portion arranged in the earth will more effectively engage the earth. For rigidly holding the post in the earth and 55 further to prevent vibration thereof, which in time would loosen the post, I provide a retaining plate 8 which is riveted to the flanges 3 and 4 in such a manner as to materially re-inforce the flanges against bending. This plate is slotted at the points 9 and 10 to provide yieldable curved flanges 11. It will be noted that the flanges 11 curve in a direction that in the forcing of the post 60 into the ground they will yield but will effectively hold the post against being removed. Owing to the area of the plate the post is held against lateral movement when pressure is brought to bear against the post or 65 the wire fence.

From the foregoing description it will be seen that by removing the rod 5 the wire fence may be forced into the slots and the rod 5 again arranged in place for effectively holding the wire fence secure to the post. 70

In the remaining figures I have illustrated the body of the post as consisting of T iron with a flange 12 riveted to the strip 13. This strip is provided with slots 14 which co-operate with the rod 15 for holding the wire 80 fence in place. In this particular instance I use a rectangular retaining plate 16 which acts in conjunction with the anchoring plate 17 arranged below the plate 16.

It is, of course, to be understood that the 85 invention may be constructed in various other manners and the parts associated in different relations and, therefore, I do not desire to be limited in any manner except as set forth in the claim hereunto appended. 90

Having thus described my invention what I claim is:

A fence post formed of sheet metal having laterally extending flanges, the vertical edges of which are bent back to form curved 95 open beads, and a retaining plate secured to the post and having curved flanges arranged contiguously to the beads but bent in opposite direction.

In testimony whereof I affix my signature. 100

WILLIAM J. DOLAN.
